FIG. 6.

INVENTOR:
EARL V. COULSTON

By
K. Mestel,
ATTORNEY.

UNITED STATES PATENT OFFICE.

EARL V. COULSTON, OF ROCK ISLAND, ILLINOIS.

STOVE-TOP CONSTRUCTION.

Application filed December 8, 1922. Serial No. 605,561.

To all whom it may concern:

Be it known that I, EARL V. COULSTON, a citizen of the United States, resident of Rock Island, county of Rock Island, and State of Illinois, have invented new and useful Improvements in Stove-Top Constructions, of which the following is a specification, the principle of the invention being herein explained and the best mode in which I have contemplated applying that principle, so as to distinguish it from other inventions.

My invention relates to the construction of the tops of cooking stoves and particularly to the outer frames thereof.

The object of said invention is to produce a stove-top frame simple in structure and economical of manufacture, and which will also eliminate breakage.

A cooking stove top consists primarily of an outer frame which extends completely around the stove, together with the loose inner pieces such as the lids and cross-pieces for which said frame forms a container.

Said frame also provides the means to which the vertical side, front and back plates of the stove are secured.

These top frames have heretofore been commonly made of cast iron either in sections bolted together or in one integral piece. The casting of such frames is relatively expensive and does not admit of much if any saving in quantity production. Furthermore, these cast iron frames are easily broken in shipping due to this fact. Such tops also frequently break in use as a result of expansion due to heating.

To overcome these heretofore existing difficulties and objections, my invention contemplates the construction of a stove top frame having all of the required characteristics of form, constructed of wrought metal and substantially wholly of standard structural steel "shapes" such as angle-iron and channel-bars.

The said invention consists of means hereinafter fully described and particularly set forth in the claims.

The annexed drawing and the following description set forth in detail certain means embodying my invention, the disclosed means, however, constituting but one of the

various mechanical forms in which the principle of the invention may be applied. 55

In said annexed drawing:

Fig. 1 represents a plan of a stove-top embodying my invention, the loose cross-pieces and lids being shown in dotted lines.

Fig. 2 represents a fragmentary plan of 60 a modified form.

Fig. 3 represents, upon an enlarged scale, a detail plan of a fragmentary portion of the frame.

Fig. 4 represents a section taken upon the 65 plane indicated by line IV—IV in Fig. 3.

Fig. 5 represents a plan of a fragmentary portion of angle-iron showing its construction prior to being bent into shape for forming the frame. 70

Fig. 6 represents a plan of another fragmentary portion of the frame.

Figs. 7 and 8 represent sections similar to that of Fig. 4 and illustrating further modifications. 75

Referring first to Figs. 1, 3 and 4, the illustrated embodiment of my invention includes an outer rectangular frame-member 1 made from angle-iron, one leg 2 of which forms a part of the top surface of the stove 80 and the other leg 3 of which forms an outer and downwardly extending peripheral strengthening flange, as shown in Fig. 4.

This frame-member may consist of a single strip of angle-iron provided, before being bent into rectangular shape, with right-angular notches 4, Fig. 5, intersecting the upper leg 2, the ends of the strip being formed with a right-angular bevel as shown in Fig. 6. This strip is then bent into rectangular form so as to close the notches and the beveled ends 5—5 welded to each other, all as will be readily understood and seen from an inspection of Fig. 1. The seams formed by the closing of the notches 4, may 85 or may not be closed by welding.

As will also be understood, the frame may be made of four separate pieces joined at the corners by welding.

Secured to the bottom of the part 2 of the 100 frame is a second frame 6 formed of angle-iron, the one leg 7 of which extends beyond the inner periphery of frame-member 1, Figs. 3 and 4, to form a dropped offset 8, the other leg forming a downwardly extending flange to which the side, front and back 105

plates of the stove may be secured, as shown in dotted lines in said figure. The offset 8 provides the required depression for receiving the loose top members of the stove.

5 Frame 6 is preferably secured by spot welding.

This frame 6 may be made of a single strip of angle-iron or of separate pieces welded together, as will be understood.

- 10 In Fig. 7 I have shown a channel-bar construction of the frame 6, which may be substituted for the angle-iron construction, and in Fig. 8 I have shown a combination of angle-bar and flat plate which may be used if desired. Both these modified forms of construction are the same in principle as that first described and involve the use of wrought metal parts exclusively.

The smoke-pipe connection 9, Fig. 1, may 20 be suitably secured to the back of the frame-member 1, which permits the smoke-pipe to be hidden behind the high shelf or closet (not shown) of the stove, as will be understood by those skilled in the art.

25 The old form of smoke-pipe connection may be provided for as shown in Fig. 2. In this form the frame-member 1 is made to extend backwardly beyond the back of frame 6 whereby they are separated horizontally.

30 An additional frame-member 10 of angle-iron is secured to the bottom of such rear portion of frame 1 and projects inwardly therefrom to provide a dropped offset for a flat steel rectangular strip (not shown) 35 which may be placed across the rear of the top and in which the smoke-pipe connection may be made as shown by the dotted line 11.

What I claim is:

1. A stove-top frame made entirely from 40 wrought metal and provided with an outer peripheral downwardly extending strengthening flange, an inner peripheral member forming a dropped offset, and an inner downwardly extending flange to which the stove sides may be secured.

2. A stove-top frame made from originally separate pieces of wrought metal and secured to each other so as to form an outer peripheral downwardly extending strengthening flange, an inner peripheral member forming a dropped offset, and an inner downwardly extending flange to which the stove sides may be secured.

3. A stove-top frame consisting of the 55 combination with a main member made of angle-iron and having one of its legs forming an outer peripheral downwardly extending flange, the other leg forming the top of said frame; of means made of wrought metal secured to the under side of said top

leg and forming an inner downwardly extending flange and a dropped offset adjacent to the inner periphery of said top leg.

4. A stove-top frame consisting of the 65 combination with a main member made of angle-iron and having one of its legs forming an outer peripheral downwardly extending flange, the other leg forming the top of said frame; of a second wrought metal member secured to the bottom of said main member, having a portion extending downwardly and a portion extending inwardly from said main member to form a dropped offset.

5. A stove-top frame consisting of the 75 combination with a main member made of angle-iron and having one of its legs forming an outer peripheral downwardly extending flange, the other leg forming the top of said frame; of a second angle-iron member secured to the bottom of said main member, having one of its legs extending downwardly from said main member and its other leg extending inwardly to form a dropped offset.

6. In a stove-top construction, the combination with a main member consisting of a strip of angle-iron bent and having its ends secured to each other so as to form a closed main rectangular frame-member, the one leg of such angle-iron forming an outer 85 peripheral strengthening flange and the other forming the top of said frame-member; of a second frame member of angle-iron, secured to the bottom of said main frame member and extending inwardly 90 therefrom to form a dropped offset, and downwardly therefrom to form a flange to which the stove sides may be secured.

7. In a stove-top construction, the combination of a main member consisting of a 100 strip of angle-iron bent and having its ends secured to each other so as to form a closed rectangular frame member, the one leg of such angle-iron forming an outer peripheral strengthening flange and the other forming the top of said frame-member; a second frame-member secured to the bottom of said main member, forming a downwardly extending flange and extending inwardly to form a dropped offset; the rear portions of 105 said two members being separated from each other horizontally; and a third frame member secured to the bottom of the rear portion of said main member and projecting inwardly therefrom to form a second dropped offset.

Signed by me this 26th day of October, 1922.

EARL V. COULSTON.
